DOUBLE SOLE ATTACHMENT FOR
KNITTING MACHINES

William G. Wilson, near High Point, N. C., assignor to Maurice Mills Company, Thomasville, N. C., a corporation of North Carolina

Application February 19, 1934, Serial No. 712,049

3 Claims. (Cl. 66—134)

This invention relates to an attachment for all types of circular knitting machines and more especially to an attachment adapted to be associated with a model R. I. Scott & Williams, ribbed 5 inverse knitting machine so as to permit an additional strand of yarn to be placed into the knitting of the sole of a stocking so as to provide a double sole for a ribbed stocking. On account of the peculiarity of a ribbed inverse knitting machine it has been heretofore impossible to place the double sole in the stocking knitted by said machine on account of the fact that by floating the doubled soled yarn across a portion of the course the floating threads will become engaged with the dial 10 needles of the machine and seriously damage the same.

It is an object of this invention to provide means whereby additional yarn can be knitted into the sole of the foot portion of a ribbed stocking produced by a ribbed inverse knitting machine.

It is a further object of this invention to provide an additional yarn cutter which may be attached to any circular knitting machine for cutting any additional yarn which may be fed to the needles.

It is still another object of this invention to provide an additional yarn cutter for attachment to a circular knitting machine for severing an additional yarn fed to the knitting needles while the dial needles are in operation.

While I have shown the invention attached to a ribbed inverse knitting machine, I desire it to be understood that the invention may also be applied to any circular knitting machine.

The invention, not only may be employed for placing a double sole in a stocking but may be used for many other purposes, such as producing pattern effects and the like, as it is evident that a cam 40 43 could be employed having several high places thereon for operating the scissors 70 for each time the additional yarn is fed to and withdrawn, from the needles.

Some of the objects of the invention having been stated, other objects will appear as the description proceeds, when taken in connection with the accompanying drawings, in which:—

Figure 1 is an elevation of the top portion of a ribbed inverse knitting machine and showing 50 my attachment applied thereto;

Figure 2 is a vertical sectional view taken through the nearest portion of the apparatus shown in Figure 1 along the line 2—2 in Figure 1;

Figure 3 is a horizontal sectional view looking 55 downward along the line 3—3 in Figure 1;

Figure 4 is a horizontal sectional view taken along the line 4—4 in Figure 1;

Figure 5 is an isometric view of a lever for operating the additional yarn cutter and clamp which I have attached to the machine;

Figure 6 is an isometric view of the means for mounting a support for the additional cutter and gripper;

Figure 7 is an outline view of a stocking made in accordance with my invention.

Referring more specifically to the drawings, the numeral 10 indicates a conventional latch ring bracket having pin 11 therein on which is pivotally mounted extension 12 for supporting the dial frame. The dial frame 13 is supported 15 by dial cap 13a which is supported by cross-head 34. Extension 12 has pivotally mounted thereon as at 15 a cutter lever 16 which has connected to the right hand end thereof a link 17 which operates conventional yarn cutter 18. 20

The knitting machine has a plurality of yarn fingers 19 and 20, only two being shown, but usually four or more of said yarn fingers are employed. Yarn finger 19 feeds double sole yarn 21 to the needles and yarn finger 20 feeds the 25 heel and toe yarn 22 to the needles. There is also of course similar yarn fingers, not shown, for feeding the leg yarn and top yarn to the needles and of course in some machines some additional fingers are employed for other purposes. 30

The yarn fingers are operated by push rods 23 which are operated by a pattern drum, not shown. The yarn fingers are normally pulled towards operative position to feed the yarn to the 35 needles by means of tension springs 24. A suitable yarn guide plate 26 is provided through which the various yarns are passed before being conducted to pass through the ends of the yarn feed fingers 20 and the like. The yarn feed fingers are pivotally mounted as at 27.

A conventional scissors has a movable blade 27a which is pivoted on screw 28 and is frictionally forced against stationary cutter 29 by means of tension spring 30. The portion 30 is secured 45 on boss 31 of the dial cap 13a. Boss 31 is rotatably penetrated by a shaft 32 and immediately above boss 31 is loosely mounted a collar 33 and loosely disposed around shaft 32 is a cross-head 34 which in turn supports hub 35 of gear 36, 50 gear 36 being driven by suitable connections with the knitting machine for imparting rotating movement to shaft 32. Disposed immediately above gear 36 are portions 37 and 38 of the stationary frame, portion 37, having an upstanding 55

projection 39 and having a plate 40 secured to the upper end thereof which confines a plate 41, connected to the broken away projection on the right hand end of cross-head 34. Immediately 5 below portion 41 there is fixed on shaft 32, a cam hub 43 which has a high place 44 thereon.

It will also be noted that the machine is also provided with a conventional thread clamp 45, secured on top of dial cap 13a by means of a 10 screw 46. A cam 47 is provided for guiding the 15 yarn beneath clamp 45.

The dial has a plurality of dial needles 49 mounted therein for engaging the yarn fed to the needles, and performing the ribbing operation.

The yarn feeding fingers 19, 20 and the like, are shown in partially raised or completely raised position, they having their right hand end, in Figure 1, resting on throat plates 50 when they 20 are in lowermost position where they feed the 25 yarn to the needles.

The above described parts are conventional and are recited in order to enable any one skilled in the art to understand my invention as applied 25 to these conventional parts.

In order to properly feed the double sole yarn to the machine for manipulation by the attachment to be hereinafter described, I provide a 30 yarn guide 68 having an eye 61 therein through which the double sole yarn 21 is passed on its way to the yarn feed finger 19. This prevents the yarn from becoming entangled with the other 35 yarns being fed to the knitting machine. Secured to a cross-head 34 is a bracket 62 having horizontal portions 63 and 64 which are slotted to receive a link 65, the slots in portions 63 and 64 being closed by suitable plates 66 and 67 to 40 slidly confine link 65 in the slot. The lower end of link 65 has fixedly secured thereon a 45 scissors blade 68, by means of a shoulder screw 69 and mounted for oscillation on shoulder screw 69, is a movable scissors blade 70 which is frictionally held against the fixed blade 68 by means of a tension spring 71. The movable scissors 50 blade 70 has an upstanding portion 73 which penetrates a slot in the horizontal portion 74 of a U-shaped lever having a vertically disposed portion 75, and an upper horizontally disposed portion 76 having a hole 77 therein which is penetrated by a shoulder screw 78 which is mounted in portion 38 for loosely confining this peculiar 55 U-shaped lever for operation. The upper horizontal portion 76 of U-shaped lever has a cut-away portion 78a therein which is adapted to be disposed in the same horizontal plane as the 60 higher place 44 of cam 43, the cutaway portion 78 being opposite upwardly projecting portion 39 which prevents the portion 76 from engaging up-standing portion 39 when portion 76 is oscillated 65 by riding over high point 44 of cam 43.

The link 65 is normally moved downwardly by means of a tension spring 80 secured to pin 81 at its upper end and to pin 82 in vertically disposed portion 62. The upper end of link 65 is 65 pivotally connected to one end of a lever 83 which is pivotally mounted as at 84 in a bracket 85 fixed on a projecting portion of cross-head 34 and the right hand end of lever 83 in Figure 2, projects beneath the right hand end of cutter 70 lever 16, as seen in Figure 1. Cutter lever 16 is normally held in elevated position as at its right hand end in Figure 1, by means of a tension spring 86. The peculiar U-shaped lever shown in Figure 5 is caused to follow cam 43 and high place 44 by means of a tension spring 87 fixed

at one end to pin 88 on horizontal portion 74 and at its other end to pin 89 in cross-head 34. The fixed blade 68 has a heel portion 68a which serves as a clamp for the yarn when it is cut by the conventional cutter 18. 5

During the knitting of the toe portion of the stocking and up to the point 1 in Figure 7, heel and toe yarn 22 is fed to the needles of the knitting machine, and during this time the right hand end of lever 16 is raised, closing the conventional cutter 18 and of course this allows the right hand end of lever 83 in Figure 2, to be raised, lowering link 65. At this point a yarn change is effected and yarn feed finger 20 is elevated to withdraw the yarn 22 from the needles 15 and yarn feed finger 19 is lowered to feed yarn 21 to the latch needles. The body yarn not shown, is also simultaneously fed to the latch needles and dial needles. With this operation conventional scissors 18 are moved to open and then 20 closed position to sever the outgoing toe yarn and link 65 is lowered to clamp the end of the severed outgoing yarn at 68a. As scissors 18 is moved to open position, this raises portion 68 and allows the toe yarn to pass beneath portion 25 68 to be clamped by portion 68a as the conventional scissors close. Then it is seen that oscillation of lever 76 by high place 44 on cam 43, will open and close scissors 70 at each revolution of the machine. At the same time the additional body yarn for knitting the foot portion of the stocking is fed to the machine by a yarn feed finger, not shown. This causes the body yarn to be fed continuously to the latch and dial needles but upon each revolution of the 35 latch needle cylinder, the additional scissors which I have added to the machine, open and close to sever the reinforcing or double sole yarn.

This operation continues until point 2 is reached at which time lever 16 is again oscillated 40 which raises link 65 and lowers link 17 to open the scissors 18. The yarn change is of course effected at the same time to again feed the toe yarn to the machine while heel 3 is being knitted. 45 No other yarn is fed to the needles while the heel portion 3 is being knitted. When point 4 has been reached, the toe yarn is withdrawn from the needles and a body yarn is fed at the same time the reinforcing yarn 21 is again fed to the 50 needles along with the regular body yarn, and the mechanism operates in the same manner as for the foot portion. When the point 5 has been reached the yarn feed finger 19 is raised after the last course of yarn 21 has been fed to the 55 needles and the body yarn is continued to be fed to the needles. Knitting continues with scissors 18 remaining in closed position throughout the knitting operation until the point 6 is reached. At point 6 a yarn change is effected to substitute a top yarn for the body yarn. 60

During normal operation of the machine, scissors 18 remains in closed position of course, lowering link 65 supporting the auxiliary cutter, the conventional cutter opening only upon a yarn 65 change.

It should be noted that when the extra sole 70 yarn is placed in the stocking that the clipper 70 cutter 18 clips the yarn 21 at a predetermined point each time the cam 44 makes a rotation, thereby placing the extra thread only in a certain portion of each course of the stocking. By clipping the yarn at each revolution, the stocking is knitted in finished form and there is no floated 75

yarn to be clipped after the stocking has been completed.

In the drawings and specification there has been set forth a preferred embodiment of the invention, and although specific terms are employed, they are used in a generic and descriptive sense only, and not for purposes of limitation, the scope of the invention being set forth in the appended claims.

10 I claim:

1. In a knitting machine having cylinder needles and dial needles, a dial and a dial shaft, a plurality of yarn fingers for feeding yarn to the cylinder needles, a yarn cutter disposed inside 15 the needle circle and operable upon each yarn change, a second cutter disposed inside the needle circle and operable upon each revolution of the needles, one of the yarn fingers having a splicing yarn therein to be fed to one-half of the cylinder needles to re-enforce one side of the stocking, a cam on the dial shaft, means operable by said cam for opening and closing the second 20 yarn cutter upon each revolution of the needles to cut the additional yarn at the point where it is withdrawn from the needles, and means for normally holding the first cutter in closed position, and means operable by the means for holding the first yarn cutter in closed position for allowing the second yarn cutter to assume a lowered position to engage the splicing yarn when it is withdrawn from the needles.

2. In a knitting machine having cylinder needles and dial needles, means for rotating the cylinder needles, a dial and a dial shaft for rotating the dial needles, a plurality of yarn fingers for feeding yarn to the needles, a cutter on the dial for cutting the body yarn when it is withdrawn from the needles, an additional yarn finger for feeding a splicing yarn to the needles for

approximately a half-course to re-enforce the sole of a stocking, an additional yarn cutter mounted on the dial for severing the splicing yarn when it is withdrawn from the needles, a clamp for holding the splicing yarn until it is again fed for a half-course of knitting whereby no loose ends are floated to become entangled in the dial needles, means for raising the additional yarn cutter and opening the first yarn cutter upon withdrawal of the body yarn and for lowering the additional cutter and closing the first cutter upon presentation of the body yarn to the needles, a cam on the dial shaft, and means driven thereby for opening and closing the additional yarn cutter upon each revolution of the 15 needles.

3. In a knitting machine having cylinder and dial needles, means for revolving the cylinder needles, a dial shaft for revolving the dial needles, a plurality of yarn fingers for feeding body 20 yarn to the needles, a yarn finger for feeding a splicing yarn to the needles, a yarn cutter mounted on the dial for cutting the body yarn when it is withdrawn from the needles, means for normally holding the cutter in closed position and 25 for opening the same to receive the body yarn when it is withdrawn from the needles, a second yarn cutter mounted on the dial and being vertically movable so the body yarn will pass thereunder when it is withdrawn from the needles, said second cutter having a portion adapted to engage the dial and clamp the body yarn after it has been cut by the first cutter, a cam on the dial shaft for opening and closing the second cutter upon each revolution of the needles, and 30 means operable by the means for opening the first cutter for raising the second cutter so the withdrawn body yarn may pass thereunder.

WILLIAM G. WILSON.
